UNITED STATES PATENT OFFICE.

HYMAN R. ROGALSKY, OF BRADFORD, PENNSYLVANIA.

SAFETY DEVICE FOR CUFF-BUTTONS.

1,139,137.

Specification of Letters Patent. Patented May 11, 1915.

Application filed July 21, 1914. Serial No. 852,149.

To all whom it may concern:

Be it known that I, HYMAN R. ROGALSKY, a citizen of the United States of America, residing at Bradford, in the county of Mc-5 Kean and State of Pennsylvania, have invented certain new and useful Improvements in Safety Devices for Cuff-Buttons, of which the following is a specification.

This invention relates to safety devices 10 for cuff buttons, and one of the principal objects of this invention is to provide a device of simple construction to be attached to the shank of an ordinary cuff button between the two layers of the cuff to prevent the 15 accidental loss of the cuff button owing to the liability of the small shoe or portion opposite the head becoming disengaged from the button hole of the cuff.

The use of ordinary link cuff buttons with 20 double or negligée cuffs worn in the summer leads to the loss of many valuable cuff buttons, and it is one of the objects of this invention to provide a device of simple construction and of attractive appearance to 25 be connected to the shank of the button between the head and shoe thereof and between the layers of the cuff to prevent the shoe or smaller portion of the button from becoming detached and the button lost. It 30 will be understood however that the safety device may be used to advantage with any form of cuff and thus prevent the loss of the button.

The foregoing and other objects may be 35 obtained by means of construction illustrated in the accompanying drawing, in which:—

Figure 1 is a view showing the cuff in section and the safety device applied to the 40 shank, the button and the latter being shown in section. Fig. 2 is an end view of the cuff and showing the safety device connected to the shank of the button between the two layers of the cuff. Fig. 3 is a plan view 45 of the safety device with the finger hold shown in section, and Fig. 4 is an edge view of the same with the finger hold complete.

Referring to the drawings the numeral 1 designates the head of a button, which may 50 be of any suitable form and 2 is the small portion or shoe. The shank 3 which con-

ncts the head and shoe may be curved or straight, and the safety device is adapted to connect with the shank between the two layers of the cuff as shown in Fig. 2. 55

The safety device is made from a single piece of wire, preferably resilient, and this wire may be plated or of solid material. The wire strand from which the device is formed is bent to form two substantially 60 semi-circular portions 4 of any required diameter, and these portions are then bent inwardly at 5 to form the overlapping portions 6, and from this point is bent oppositely and outwardly to form the loop 7, one 65 portion of the loop overlying the other. The two strands of wire are then brought together and bent around the center of the semi-circular portions 4 where they terminate in a loop 8 which surrounds an inwardly bent portion 9 of the wire. A sheet metal finger hold 10 covers the terminal 70 ends of the wire and makes a finish for the device, the finger hold 10 being bent around the ends as shown more clearly in Fig. 4. 75

In use the two overlapping portions 6 and 7 are sprung apart by inserting the shank 3 of the button between the two members 5 and pushing the device on until the portions 6 separate and permit the shank to lie 80 in the recess 11 between the two members 7 of the loop, thus rendering it impossible for the cuff button becoming accidentally detached from the button holes of the cuff a. By grasping the finger hold 10 the safety 85 device may be readily detached from the cuff button shank whenever desired.

The device is simple in construction is attractive in appearance and can be quickly attached and detached to and from the shank 90 of the button.

Various changes may be made in the detail of construction without departing from the spirit and scope of the invention as described in the claim. 95

What is claimed is:—

A safety device for cuff buttons comprising two overlapping semi-circular members formed from a single strand of resilient wire, said semi-circular members each being 100 provided with a centrally disposed loop to engage the shank of a cuff button, the ends

of the wire being bent around the body portion of the device at a point centrally opposite the loop, and a sheet-metal finger-hold secured to the body portion of the device and covering the ends of the wire, the two semi-circular portions having a divergent guide for the shank of the button.

Copies of this patent may be obtained for five cents each, by addressing the "Commissioner of Patents, Washington, D. C."

In testimony whereof I affix my signature in presence of two witnesses.

HYMAN R. ROGALSKY.
